UNITED STATES PATENT OFFICE.

FRANK EDWARD MEYER, OF SALT LAKE CITY, UTAH.

CHILD'S VEHICLE.

Application filed October 25, 1922. Serial No. 596,803.

To all whom it may concern:

Be it known that I, FRANK EDWARD MEYER, a citizen of the United States, residing at Salt Lake City, in the county of Salt Lake and State of Utah, have invented a new and useful Child's Vehicle, of which the following is a specification.

This invention relates to a child's vehicle with an aeroplane body mounted thereon.

16 The object of this invention is to provide a vehicle for children with an aeroplane body so that the child can sit within the aeroplane body and push himself along by his feet treading on the ground.

15 This invention consists of the following construction of parts to be fully described and claimed.

Referring to the drawings, in which; Figure 1 is a side view of the invention. 20 Fig. 2, is a plan view of the bottom B. Fig. 3, is a front view of the invention. Fig. 4, is a section on line 4—4 Fig. 1. The reference character A denotes the aeroplane body of the vehicle. A' the opening within the body which is formed by the 25 sides, top, and bottom of the body A and also containing the cock pit and B the bottom of the body. Notches 18 and 19 cut in the bottom B permit free use of the child's legs 30 when it straddles the bottom B and is sitting on the bottom at B' or standing on the ground.

The top plane C is located above the body A while the bottom plane C' is secured to the side of the body by bolts (not shown). 35 Supports 30 and 30' connect the top plane C with the bottom plane C' while supports 31 and 31' connect the top plane with the body A.

40 On the rear end of the body A is located the rudder D which is hingedly secured to the fin F by straps 32 and 32'. The elevator E is hingedly secured to the tail plane E' by straps 33.

45 On the front end of the body A is located the propeller G which is secured to the frame by the bolt 32.

50 Located on the upper plane C are the right aileron R and the left aileron L which are secured thereto by any ordinary means as straps 34.

55 Braces H support the frame A while the stay wires J secure the frame and braces together. The frame may be covered with cloth or any other suitable material.

On each side of the cock pit 35 are hingedly secured to the frame the doors K and K'. The door K is shown broken away with the section shown hinged to the frame at 39. While shown from the door K' is the handle 40 for holding the door closed which is operated from the outside or from the inside of the body A. The doors must be opened before the child can enter the enclosure of the body which is located between the braces H just forward and aft of the openings 18 and 19. This compartment is open at the front to permit the child to reach the steering handle 17, and is also open at the back so that the child can carry whatever is desired within the compartment.

A hole 21 is cut in the bottom B of the frame A for receiving the upper end of the stock 4, the lower end of the stock 4 having a fork thereon in which is journaled the 75 wheel 1 by means of the pin 3. Placed over the stock 4 and under the bottom B is a washer 5. Placed over the stock 4 and above the bottom B and within the frame are the washers 6 and 7, secured to the stock by a pin 8. The washers 5 and 6 have a taper thereon to fit the taper of the bottom B. The washer 7 can be placed under the washer 5 if so desired. Projecting from the back of the stock 4 is a lug 9' that represents the tail skid of the aeroplane.

A hole 2 is made in the bottom B through which is placed the handle or upper end of the stock 13. The lower end of the stock 13 has a fork 12 thereon. 90 Through the fork 12 passes a shaft 11 the ends thereof having wheels 10 thereon. A washer 14 is placed over the stock 13 and below the bottom B. Another washer 15 is placed over the stock 13 on the inside of the frame A. A hole in the upper end of the stock 13 receives the handle 17.

Having thus described the parts of my invention I will now illustrate the operation of same by the child.

The child in getting into the vehicle opens one of the doors K placing one leg over the bottom and passing it through the opposite slot. Now the child sits down on the bottom and within the cock pit 35 with its head above the frame so that it can see over the top of the plane C and places its hands upon the handle 17 that is within the body A. Now the child will move its feet upon the ground as in walking and

the vehicle will roll on the wheels and in any direction the child desires it to go by its turning the stock 13 with the handle 17.

Having thus described my invention 5 what I claim as new and desire to secure by Letters Patent, is;

1. A child's vehicle of the character described having an aeroplane body, said body having doors thereon, a stock attached to said body back of said doors, 10 said stock having a wheel pivotally journaled therein and a lug thereon, said lug to represent the landing skid of the aeroplane.
- 15 2. A child's vehicle of the character described having an aeroplane body, said body having doors thereon and a bottom secured thereto, a stock secured to said body back of said doors, the lower end of 20 said stock having a fork formed thereon,

said fork having a wheel journaled therein, said stock having washers on the upper end thereof, said washers being for regulating the height of said frame from the ground, said stock having a lug thereon 25 which represents the landing skid of the aeroplane.

3. A child's vehicle of the character described comprising an aeroplane body, doors secured to said aeroplane body, a stock pivotally passing through a hole in the front end of said body, steering wheels carried by said stock, said stock having a handle thereon, said handle being for steering said vehicle, means in said frame 30 for the free passage of the child's legs to the ground, and means for securing said stock to said frame.

In witness whereof I affix my signature.

FRANK EDWARD MEYER.
